UNITED STATES PATENT OFFICE

ERNEST M. BRADLEY, OF WEEDSPORT, NEW YORK

METAL PLANKING FOR RAILWAY CROSSINGS

Application filed January 19, 1931. Serial No. 509,800.

This invention relates to surface structures for railroad crossings, roadways, bridges, etc. and has for an object the provision of a metallic structure which may be mounted upon a suitable support to provide a raised roadway whose horizontal plane is the same as the tread surfaces of railroad tracks, so that the invention is especially useful for railroad crossings.

Another object of the invention is the provision of a surface structure which is composed of a number of complementary units to provide a surface of any length and width, together with simple and efficient means for connecting the units.

With the above and other objects in view, the invention further includes the following novel features and details of construction, to be hereinafter more fully described, illustrated in the accompanying drawings and pointed out in the appended claims.

In the drawings:—

Figure 1 is a transverse sectional view of a railroad track with the invention in position for use.

Figure 2 is a fragmentary top plan view of the same.

Figure 3 is a detail perspective view of one of the units.

Figure 4 is an enlarged fragmentary transverse section illustrating the manner of connecting the units.

Referring to the drawings in detail wherein like characters of reference denote corresponding parts, the reference character 10 indicates the ties of a railroad track, the rails of which are indicated at 11.

The invention comprises a number of separate units 12 which are adapted to be secured between the rails in parallelism and upon the outsides of the rail. These units each comprise elongated channel-shaped members and comprise relatively inclined side walls 13 and a top wall 14. This top wall is disposed in a plane with the treads of the rails 11 and is corrugated or roughened as shown so as to provide traction adhesion. By inclining the walls 13 in the manner shown, increased resistance against bending is provided.

Extending from the longitudinal edge of

one side wall of each of the units is a flange 15 which is provided with openings 16 for the passage of spikes or other fastening devices 17 by means of which this side of the channel-shaped unit may be secured to the ties 10. The opposite side wall 13 has extending therefrom lugs 18 and these lugs are oppositely offset so as to provide a clamping engagement over the secured edge or flange 15 of an adjacent unit, whereby the units will be securely held in position.

It will be apparent from the foregoing description and accompanying drawings that the invention provides a simple, light, durable and efficient means for constructing railroad crossings and structures of a similar character, and due to its simplicity of construction may be readily and quickly laid and securely held in position.

The lugs 18 adjacent the rails 11 engage over the edges of the base flanges of the rails so that it is only necessary to spike down one edge of each unit. The intermediate units have the lugs 18 thereon engaging over the edges of the spiked flanges of the companion units.

The invention is susceptible of various changes in its form, proportions and minor details of construction and the right is herein reserved to make such changes as properly fall within the scope of the appended claims.

Having described the invention what is claimed is:—

1. A metallic surface structure comprising a plurality of inverted channel units having the closed edges of the units disposed in the same plane, a supporting structure for said units, means to secure one longitudinal edge of each of the units to the supporting structure, and means providing an interlocking connection between the secured edge of one unit and the other edge of the next adjacent unit.

2. A metallic surface structure comprising a plurality of inverted channel units arranged in parallel relation with the closed edges of the units disposed in the same plane, a supporting structure for said units, means to secure one longitudinal edge of each of the units to the supporting structure, and

oppositely offset lugs extending from the other edge of each unit for clamping engagement with the secured edge of the next adjacent unit.

5 3. A new article of manufacture comprising a sheet shaped to provide an elongated channel member including opposite side walls, a flange extending laterally from the longitudinal edge of one of said walls and
10 having openings therein, and oppositely offset lugs extending from the longitudinal edge of the other wall.

4. A new article of manufacture comprising a sheet shaped to provide an elongated
15 channel member including opposite, relatively inclined side walls, a flange extending laterally from the longitudinal edge of one of said walls and having openings therein, and oppositely offset lugs extending from the
20 longitudinal edge of the other wall.

In testimony whereof I affix my signature.

ERNEST M. BRADLEY.
